CLAIM

The ornamental design for a fire-resistant safe, as shown and described.

DESCRIPTION

FIG. 1 is a right front perspective view of a first embodiment of an ornamental design for a fire-resistant safe according to the present invention;

FIG. 2 is a front view of the fire-resistant safe shown in FIG. 1;

FIG. 3 is a left side view of the fire-resistant safe shown in FIG. 1;

FIG. 4 is a right side view of the fire-resistant safe shown in FIG. 1;

FIG. 5 is a top view of the fire-resistant safe shown in FIG. 1;

FIG. 6 is a bottom view of the fire-resistant safe shown in FIG. 1;

FIG. 7 is a rear view of the fire-resistant safe shown in FIG. 1;

FIG. 8 is a left rear perspective view of the fire-resistant safe shown in FIG. 1;

FIG. 9 is a right front perspective view of a second embodiment of an ornamental design for a fire-resistant safe according to the present invention;

FIG. 10 is a front view of the fire-resistant safe shown in FIG. 9;

FIG. 11 is a left side view of the fire-resistant safe shown in FIG. 9;

FIG. 12 is a right side view of the fire-resistant safe shown in FIG. 9;

FIG. 13 is a top view of the fire-resistant safe shown in FIG. 9;

FIG. 14 is a bottom view of the fire-resistant safe shown in FIG. 9;

FIG. 15 is a rear view of the fire-resistant safe shown in FIG. 9; and,

FIG. 16 is a left rear perspective view of the fire-resistant safe shown in FIG. 9.
